PRESSURE ESTABLISHING MECHANISM

Charles W. Williams, Shaker Heights, Ohio, assignor to Automatic Safety Wringer Company, a partnership composed of Charles B. Williams, Shaker Heights, Horace B. Fay, Willoughby, and Charles W. Williams, Shaker Heights, Ohio

Application December 2, 1942, Serial No. 467,642

9 Claims. (Cl. 68—253)

This invention relates to a multiple roll clothes wringer and more particularly to the type of wringer in which the pressure is shifted from one roll bite to another as the feeding of clothes through the wringer is reversed. This application is a continuation in part of my application Serial No. 143,524, filed May 19, 1937.

The cardinal object of this invention has been to provide a simplified mechanism for interchangeably establishing pressure roll bites which function to extract liquid from material fed to the wringer from one side or the other, depending upon the position of the pressure roll bite. An additional object of this invention has been to develop shifting mechanism for reversing the direction of rotation of the rolls when the wringing pressure is shifted.

My invention may be utilized in such manner that shifting one handle control will simultaneously shift the pressure mechanism and reverse the roll rotation.

An additional object of my invention has been to eliminate the necessity for a separate latch construction to maintain the top of the wringer in operating position on the main body part. By doing this I am able to accomplish the three-fold function of stopping the roll rotation, releasing the wringing pressure and unlatching the top to permit opening of the wringer.

Other functions of this invention will become apparent from the specification and the drawings, while the essential characteristics are summarized in the claims.

In the annexed drawings:

Fig. 1 is a side elevation of my improved wringer;

Fig. 2 is a vertical section taken lengthwise through the wringer as indicated by the line 2—2 in Fig. 4;

Figs. 3 and 4 are sections through the wringer as indicated by the lines 3—3 and 4—4 on Fig. 2 respectively; and

Fig. 5 is a section through the wringer as indicated by the lines 5—5, Fig. 4 with parts omitted.

Referring now to Fig. 1, my invention comprises a driving head 10, a body portion 12 and a top 14 pivotally carried thereon at 15. A guide 16 for directing clothes in the roll bites is provided. The body portion 12 may carry spaced ears 12' pivotally carrying a bolt 12", the said bolt swinging into engagement with a bifurcated lug 14' carried by the top and held in position by a thumb screw 14" to secure the top and body portions together although such latch structure

is not essential in view of other locking means which will be described herein.

There are three rolls in my wringer as above indicated, with one of the rolls coacting with the other two to provide a pair of roll bites. This common roll, designated at 20, is shiftably carried by the top 14 in cross-ribs 22, one at each end of the wringer. These ribs are provided adjacent their mid-section with pockets 24 having vertical ribs 25. Journal blocks 28 are carried in said pockets and include pins 30, which allow the same to be vertically shiftable between the ribs 25 and yet prevent lengthwise shifting. Downward movement of the journals is prevented by a bottom portion 29 of the pockets. The roll 20 is journaled at each end in bushings 31, which in turn are carried in the journal blocks 28.

The pressure mechanism bears on the top of 20 the journals 28 to establish wringing pressure in the wringer. To this end a pair of pressure springs, one at each end of the wringer and designated at 35, are supported at one end around bosses in the ribs 22 and at the other end around 25 bosses 36 bearing against nuts 37 carried by bolts 40. The other ends of the bolts pass through the ribs 22 and terminate in forks. Bars 42, pinned to the bolts at yokes 44, bear at one end on top of the journal 28 and at the other end 30 against wear plates 46 integral with the ribs 22. The tendency of the springs 35 to expand applies pressure to the top roll 20.

The lower rolls 45 and 50, together with a guide 52, are supported in fixed bodily relation 35 to each other by a pair of double journal blocks 51. The double journal blocks and the rolls they carry are normally held upward in position to coact with the roll 20 by light springs 56, completely described in my Patent No. 2,197,-

402 as shown at 56 in Fig. 3 thereof. To limit the longitudinal shifting of the journal blocks 51 and their rolls 45 and 50 two sets of channel members 59 are provided. The bottom portion of each of the channels is secured 45 to the side wall of the wringer and the outstanding portions provide a bearing against which the journal blocks 51 abut, thus limiting their longitudinal displacement.

Connecting the tops of the channel irons 59 above the journal blocks 51 are channel plates 59' against which bearing blocks 51 engage when the top is open to prevent displacement of the lower rolls from the body portion.

A rock arm carried by the top 14 is employed 55 to shift the mechanism to alternately establish a

pressure roll bite between the top roll 20 and either of the lower rolls. As shown in Fig. 4, there are provided two rock arms 55 connected by a handle 55', the rock arms being integral with bearings 57 pivotally mounted in the upper frame. A substantially triangular opening 58 is provided in each rock arm to permit the roll 20 to shift upwardly without encountering resistance from rock arms. The opening 58 is triangular to permit free upward movement of the roll for any position of the handle 55. Thus, while the handle is not bodily shiftable in the top 14, the roll 20, the shaft of which passes therethrough, is vertically shiftable in the top.

The rock arms 55 are T-shaped at the bottom to provide bearings when the handle is shifted to underlie either of the lower rolls. As shown in Fig. 4, this T-shaped portion, designated at 60, has been shifted to the right and a pressure roll bite established between the rolls 20 and 50. To accomplish this, the T-portion has been moved to underlie the said roll shaft until the same reposes in cup-shaped depression 62 of the T-head. When in this position the roll 50 has been pulled upwardly into engagement with the roll 20 and forced the same upwardly away from the bottom of the pockets 29 against the pressure springs 35 to establish the aforementioned wringing pressure at this bite. When the handle 55 is thrown to the other position the T head 60 releases the roll 50 and engages the shaft of the roll 45 by the pockets 62' to create a pressure bite between the rolls 20 and 45. It will be noted that when the handle 55 is vertical, pressure is released from both of the lower rolls and the top may be opened drawing the T head 60 upwardly between the adjacent roll shafts. In this manner the handle 55 functions as a latch to keep the wringer closed and the top and body are unlatched by shifting the handle to a neutral position.

As more fully described in my patent above referred to, the roll not engaged as a pressure roll coacts with the common roll 20 to provide an auxiliary intake bite for clothes fed to the wringer. Due to the light pressure maintained at the intake bite the operator is protected from injury if her hands should pass into the bite but, due to the pinching action encountered, will instinctively withdraw her fingers and prevent them passing into the harmful pressure roll bite.

The roll rotation must be reversed as the pressure roll bite is shifted and from the standpoint of safety it is desirable that the rolls always rotate in such direction that clothes cannot be fed directly to the pressure roll bite. The mechanism about to be described is intended, not only to protect the operator from feeding clothes at the pressure bite, but to reverse the roll rotation by the handle 55 and simultaneously with a shifting of the pressure bite.

The drive to the rolls from an ordinary washing machine wringer post is transferred to the head by the connection 65 in the stub shaft 66, which at its other end carries a bevel gear 67. Two bevel gears 68 and 69 mesh with the gear 67 and are idly carried on a shaft 64. A clutch 72 is pinned to the shaft 64 and engages either gear 68 or 69 as desired by sliding the shaft 64 in its journals 70 and 70' in the head, which sliding is effected in the manner hereinafter to be described.

A double toothed gear 75, such as is common in washing machine wringer drives, is slidably carried to rotate with the shaft 64. A mating gear, also of the double toothed variety, is car-

ried by the shaft of the roll 20, as indicated at 71. Depending on which of the gears 68 and 69 is engaged by the clutch 72, the roll 20 will be driven and, due to frictional contact with it, the rolls 45 and 50 will also be rotated.

To shift the shaft 64, a clutch 80 is provided and pinned thereto at its inner end. A forked arm 82, pivotally carried by the body at 85, is provided with a pair of pins 86 which engage the clutch 80. The bottommost fork of the arm 82 is of the shape shown in Fig. 5 at 90 and is slotted as at 92 to accommodate a circular extension 94 of the T. head 60. Thus, as the handle 55' is shifted back and forth, the projection 94 slides in the slot 92 and cams the arm 82 back and forth about its pivot. This back and forth movement shifts the clutch 80 and with it the clutch 72, to establish a wringer drive in either direction desired. It should be noted that when the handle 55 is in a vertical position the clutch 72 is moved to be disengaged from both bevel gears 68 and 69, thus stopping rotation of the wringer.

A guide 52 is carried by bearing blocks 51 and lies between the rolls 45 and 50.

It will be seen from the foregoing description that I have invented a novel and safe clothes wringer in which one handle control may function to transfer wringing pressure from one roll bite to another, to unlatch the top of the wringer from the body and to reverse the roll rotation, or the wringer may be employed to accomplish any combination of these functions desired.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In a wringer, a frame, a movable top carried thereby and held in locked condition when the rolls are in wringing relation, three rolls in said wringer with one roll supported by the top and coacting with the other two to provide a pair of roll bites, pressure mechanism to apply wringing pressure at either roll bite desired, including shiftable means carried by the top and engaging either of the other two rolls, said means being operable to simultaneously release said wringing pressure from the wringing pressure bite and to disengage said mechanism from both rolls to permit moving the top with respect to the frame.

2. In a wringer, a main frame, a top frame shiftable carried thereby, a roll carried by the top frame, two rolls carried by the bottom frame, said rolls coacting to provide a pair of roll bites with the top roll as the common roll, pressure mechanism to apply wringing pressure at either roll bite desired, and rocker arm mechanism carried by said top and shiftable to underlie either under roll desired to maintain the same against the top roll and establish a pressure bite between said top roll and said under roll.

3. In a wringer, a frame, three rolls carried thereby, said rolls coacting to provide a pair of roll bites with one roll above the other two and common to both bites, rocker arm mechanism shiftable to engage either other roll desired to urge the same against the top roll and establish a pressure bite between said top roll and said other roll, together with power means to drive said rolls, reversible mechanism to reverse the direction of rotation of said rolls, and a link

connecting said reversing mechanism and said shiftable rocker arm mechanism to simultaneously reverse the direction of rotation of said rolls and establish a wringing pressure bite between the top roll and desired alternate lower roll.

4. In a wringer, a main frame, a top frame shiftable carried thereby, a roll carried by the top frame, two rolls carried by the bottom frame, said rolls coacting to provide a pair of roll bites with the top roll as the common roll, pressure mechanism normally urging said top roll downwardly, and rocker arm mechanism carried by said top and shiftable to underlie either lower roll desired to maintain the same in predetermined relation to the top roll and establish a pressure bite between said top roll and said lower roll.

5. In a wringer, a frame, three rolls in said frame with one roll coacting with each of the other two to provide a pair of roll bites, pressure mechanism including a member adapted to be manually gripped shiftable from coaction with said one roll and either of said other two rolls to establish a clothes wringing bite at either roll bite desired, reversible power means to drive said wringer including mechanism adapted to break the drive to said rolls during rotation in either direction, an arm carried by said frame for swinging movement in a plane parallel with the rolls, said arm engaging said drive breaking mechanism and means connected to said shiftable member and engaging said arm to break said drive consequent upon shifting said manual member to release the pressure mechanism from either roll bite.

6. In a wringer, a frame, three rolls in said frame with one roll coacting with each of the other two to provide a pair of roll bites, pressure mechanism including a member adapted to be manually gripped shiftable from coaction with said one roll and either of said other two rolls to establish a clothes wringing bite at either roll bite desired, reversible power means to drive said wringer including a separable connection adapted to break the drive to said rolls, and means connected with said separable connection to break said connection consequent upon shifting said manual member to release the pressure mechanism from either roll bite, said means including a forked arm carried by the frame for swinging movement in a plane parallel with the rolls and engageable by said shiftable member to break said drive.

7. In a wringer, a frame, three rolls in said frame with one roll coacting with each of the other two to provide a pair of roll bites, pressure mechanism shiftable from coaction with said one roll and either of said other two rolls to establish a clothes wringing bite at either roll bite de-

sired, power means to drive said wringer including a pair of gears, a third gear mounted transversely of said pair of gears and adapted to effect a roll drive with either gear of said pair, mechanism arranged to alternately establish a drive through said third gear and either of said pair of gears to reverse the direction of rotation of said rolls, said mechanism including a slideable shaft having a clutch thereon and means operatively engaging said shaft to simultaneously shift said pressure mechanism from one roll bite to the other and move said shaft to operatively connect said gears for reversal of rotation of said rolls.

15 8. In a wringer, a frame, three rolls in said frame with one roll coacting with each of the other two, to provide a pair of roll bites, pressure mechanism shiftable from coaction with said one roll and either of said other two rolls to establish a clothes wringing bite at either roll bite desired, power means to drive said wringer including a sliding shaft, a pair of gears idle on said shaft, clutch means keyed to said shaft for rotation therewith and adapted to be moved with the sliding shaft to engage with either of said gears as desired, a third gear mounted transversely of said pair of gears and adapted to effect a roll drive with either gear of said pair and mechanism arranged to alternately shift said clutch means from engagement with one of said pair of gears to engagement with the other of said pair of gears to establish a drive through the gear engaged by said clutch and said third gear to reverse the direction in which said rolls are rotated, and means to simultaneously shift said pressure mechanism from one roll bite to the other and operatively release said clutch means from one of said pair of gears with which engagement had been made.

20 9. A wringer comprising a frame, a roll rotatably carried in said frame, a pair of rolls adjacent said first roll, means for alternately pressing one of said adjacent rolls against said first roll to provide wringing rolls and urging the other adjacent roll toward one of said wringing rolls to provide rolls for feeding material to said wringing rolls, power means to drive said rolls including a separable connection, and a member adapted to be manually gripped and interconnected with said alternate pressing means and said separable connection including an extension on said shiftable member, a pivoted arm having a cam slot therein engaging said extension and having connection with said separable connection, said member being operative on manually shifting to release said pressing means from said wringing rolls and break said separable connection to stop the operation of the wringer.
